UNITED STATES PATENT OFFICE.

WILLIAM BIRRELL AND JAMES BIRRELL, OF CHICAGO, ILLINOIS, ASSIGNORS TO THE AUDIBLE TELEPHONE COMPANY, OF CHICAGO, ILLINOIS, A CORPORATION OF DELAWARE.

TELEPHONE-TRANSMITTER.

1,342,581.

Specification of Letters Patent. Patented June 8, 1920.

Application filed August 18, 1917. Serial No. 187,033. Renewed January 19, 1920. Serial No. 352,579.

To all whom it may concern:

Be it known that we, WILLIAM BIRRELL and JAMES BIRRELL, citizens of the United States, and residents of Chicago, county of Cook, and State of Illinois, whose post-office address is 170 W. Randolph street, have invented a new and useful Improvement in Telephone-Transmitters, of which the following is a specification.

This invention relates to improvements in telephone transmitters and more particularly to improvements in transmitters of the type shown and described in our prior patent application Serial No. 106,093, filed June 27, 1916.

An object of this improvement is to simplify the construction of telephone transmitters and to provide inexpensive means for securing or fastening together the various parts of a transmitter diaphragm of the form shown in the application above referred to.

It is an important object of this invention to provide means for firmly securing an insulating cover on the electrode chamber of a telephone transmitter by frictional means and without the use of bolts or rivets.

The invention consists in the novel construction of a telephone transmitter and in the novel means employed for securing certain of the parts in assembled condition through punching or clenching the metal of the peripheral edges of the electrode chamber over a retaining ring.

In the accompanying drawings Figure 1 is a view in vertical mid-section of a telephone transmitter constructed in accordance with this invention.

Fig. 2 is a view in sectional perspective illustrating the diaphragm and

Fig. 3 is a detached view in elevation of the rear side of the diaphragm.

Referring to the drawings throughout which like reference numerals indicate like parts the numeral 5 indicates a telephone transmitter casing having a central threaded aperture for the reception of a mouthpiece 6 and being provided with a back plate 7 secured thereto as by screws 8 and forming a closure for a diaphragm compartment 9.

10 is a circular diaphragm loosely disposed in the compartment 9. Felt blocks 11 are arranged to prevent the displacement of the diaphragm within the compartment and

also act to damp and modify excessive vibrations thereof. An insulating ring 12 of rubber or other suitable material encircles the periphery of the diaphragm 10. 55

The diaphragm is formed with a centrally disposed electrode chamber 13 having oppositely disposed carbon electrodes 14 and 15 carried on metal disks 16 that are secured to the front and rear walls of the electrode chambers by preferably integral studs 17 and 17', all of the above mentioned devices 60 being more specifically described in our co-pending application hereinbefore referred to. 65

The novel features of the device disclosed in this application resides in the form of construction of the electrode chamber 13, 70 and the manner of securing the assembled parts in their proper positions therein.

The electrode chamber consists of an outer shallow recessed portion which forms an annular wall 18 and shoulder 19, and a centrally arranged deeper portion which forms the electrode chamber proper. 75

The shallow recessed portion is adapted for the reception of a mica insulating disk 20 which rests upon the shoulder 19 and a metal washer 21 which rests upon and holds 80 the mica disk 20.

The washer 21 is large enough so that it fits tightly against the annular wall 18 of the shallow recessed portion and is thereby 85 prevented from jarring loose and rattling, it being necessary to use force in seating the washer on the mica disk.

The washer 19 is securely held in place by punching or depressing the metal of the diaphragm at several points on the perimeter of the shallow recess as indicated at 22, the depressed portions being crimped securely over and caused to bear upon the edge of the washer. 90

In this form of construction the mica disk and retaining washer are countersunk into the diaphragm instead of being on the rear face thereof, and all rivets or bolts are avoided. 95

The electrodes 14 and 15 are inserted and the electrode chamber is partially filled with carbon granules preparatory to the assembling of various parts.

In prior devices of this nature with which 105 we are familiar it has been customary to form an electrode chamber in the diaphragm and to secure the mica disk over the elec-

2
trode chamber by placing the retaining washer thereover and riveting the same to the rear surface of the diaphragm.

The diaphragm herein disclosed is cheaper to construct, neater in appearance and more substantial and efficient than the old form.

26 are wires one of which is connected to the stud 17' and the other of which is connected with the diaphragm as by a rivet 27.

10 If desired the entire perimeter of the shallow recessed portion of the electrode chamber may be clenched over the edge of the washer 21 instead of clenching the same at a plurality of different points as shown. The

15 washer 21 may also be constructed to fit so tightly in the depressed chamber that it will be frictionally held in place by the diaphragm after being forced into position.

It is obvious that changes in the form of 20 the construction of the various parts of this invention may be resorted to within the scope of the appended claims.

What we claim and desire to protect by Letters Patent is:

25 1. The combination with a transmitter diaphragm having an electrode chamber provided with a shoulder depressed from the plane of said diaphragm, of devices for closing said chamber adapted to rest on said shoulder, said closure devices being held in place by clenching the metal of the diaphragm over the edges thereof.

30 2. The combination with a transmitter diaphragm having an electrode chamber that is provided with a shoulder depressed from the plane of said diaphragm, of a mica disk adapted to close said chamber and rest upon said shoulder, and a washer positioned on said mica disk, said washer being securely held in place by clenching the metal of the diaphragm over the peripheral edges of said washer.

35 3. A device of the class described comprising a metallic diaphragm having an electrode chamber formed therein, said electrode chamber having a shallow recessed portion around the outer edge thereof that forms a shoulder and means adapted to fit within said shallow recessed portion and rest upon said shoulder to close the end of said chamber said means being securely held in position by having portions of the metal of said diaphragm clenched thereover at a plurality of points around the edge of said electrode chamber.

40 4. The combination with a thin metallic plate having an integral pocket formed therein said pocket having a shallow recessed portion around the edge thereof that forms a shoulder of a mica disk adapted to rest on said shoulder and close said pocket and a retaining washer within said shallow recessed portion upon said mica disk said

retaining washer being securely held in place by clenching the metal of said plate over the 65 peripheral edges of said washer.

5. A diaphragm for a telephone transmitter comprising a thin flexible metallic disk, an integral electrode chamber in said disk, a shallow recessed portion around said chamber and forming an annular wall and a shoulder, a mica disk adapted to rest on said shoulder and close said chamber, a retaining washer positioned on said disk, said retaining washer being adapted to fit tightly 75 against said annular wall to prevent rattling and means for holding said washer said means being formed by clenching portions of the metal of said disk around the perimeter of said electrode chamber over the 80 peripheral edge of said washer.

6. A diaphragm for a transmitter comprising an annular disk of thin metal, a shallow portion depressed from the plane of said disk to form an annular shoulder, a deeper 85 portion depressed from the plane of said disk concentric to said shallow portion to form an electrode chamber, a small diaphragm disk adapted to rest on said shoulder and within said shallow depressed portion to close said chamber and an annular retaining washer disposed to rest on said small diaphragm disk and fit tightly within said shallow recessed portion, the outer surface of said washer being slightly below 95 the plane of said annular disk and the metal of said annular disk being clenched over the edges of said washer at a plurality of points around the edge of said shallow depressed portion to securely hold said washer. 100

7. The combination with a transmitter diaphragm having an electrode chamber depressed from the plane thereof, of an insulating disk in the chamber and a metal ring frictionally held in the chamber for 105 securing the insulating disk in position.

8. The combination with a thin metallic plate having an integral pocket formed therein and a shoulder formed around the edge of said pocket of insulating means 110 adapted to rest on said shoulder and close said pocket, and frictionally secured retaining means for holding the insulating means in place.

9. A device of the class described comprising a metallic diaphragm, a central cylindrical chamber depressed from the plane of diaphragm, a second chamber integral with and of less diameter than the first mentioned chamber, and insulating means secured in 115 first chamber to close the second chamber.

Signed at Chicago, Illinois, on the 14th day of Aug., 1917.

WILLIAM BIRRELL.
JAMES BIRRELL.
